UNITED STATES PATENT OFFICE.

WILLARD C. SMITH AND B. DUANE JOSLIN, OF KINDERHOOK, MICHIGAN,
ASSIGNORS OF ONE-THIRD OF THEIR RIGHT TO RICHARD LOBDELL AND
FLINT LOBDELL.

SOLDERING-IRON.

SPECIFICATION forming part of Letters Patent No. 228,000, dated May 25, 1880.

Application filed March 12, 1880. (Model.)

To all whom it may concern:

Be it known that we, WILLARD C. SMITH and B. DUANE JOSLIN, of Kinderhook, in the county of Branch and State of Michigan, have 5 invented an Improvement in Soldering-Irons, of which the following is a specification.

The nature of this invention relates to certain new and useful improvements in the construction of soldering-irons; and the invention 10 consists in the peculiar construction and arrangement of parts, all as more fully hereinafter set forth.

In the drawings, Figure 1 is a longitudinal central section. Fig. 2 is a cross-section at *x* 15 *x*. Fig. 3 is a cross-section at *y* *y*. Fig. 4 is a modification of Fig. 1.

In the accompanying drawings, which form a part of this specification, *A* represents a hollow handle, provided with a feed-pipe, *B*, the 20 outer end of which is provided with a jet or burner, *C*. Within this feed-pipe is a small perforated pipe, *D*, which is surrounded by a proper wick, *E*.

The outer end of the feed-pipe *B* is exteriorly threaded to screw into one end of the perforated cylinder or generator *F*, which is in turn threaded into the head *G*, in which is formed a recess, the walls of which are perforated, as shown, and over these perforations 30 is placed a wire screen, *V*, within the recess in the head.

In practice, the parts being constructed as herein described, the handle *A* is filled with any suitable volatile inflammable liquid. From 35 the handle, the liquid is carried to the jet or burner *C* by means of the wick and feed-pipe, where, mingling with air entering through the perforations in the generator *F*, it is converted

into gas or vapor, is ignited in any convenient manner, and heats the head *G*, the heated currents passing out through the perforations in the head. 40

It will be seen that the perforated pipe *F* can readily be adjusted on the feed-pipe *B* by means of the screw-threaded connection of the 45 pipes, whereby more or less air can be admitted to the jet *C*, as desired, to regulate the combustion.

In Fig. 4 a modification is shown, wherein the outer end of the cylinder *F* is formed into 50 a head for use in small work.

What we claim as our invention is—

1. The combination of the hollow handle *A*, feed-pipe *B*, carrying the jet *C*, adjustable pipe *F*, provided with perforations communicating directly with its interior and with the outer air, and perforated soldering-head *G*, substantially as described, and for the purpose 55 set forth.

2. The combination of the hollow handle *A* and feed-pipe *B*, carrying the jet *C* in its outer end, the adjustable pipe *F*, provided with perforations communicating directly with the interior of pipe *F* and with the air, and the recessed and perforated head *G*, substantially 60 as described, and for the purpose set forth.

3. In a soldering-iron, and in combination with the hollow handle *A* thereof, the feed-pipe *B*, jet *C*, perforated cylinder *D*, wick *E*, generator *F*, and perforated recessed head *G*, 65 substantially as and for the purposes specified. 70

WILLARD C. SMITH.
B. DUANE JOSLIN.
